UNITED STATES PATENT OFFICE.

LEWIS LAVUS A. MAYALL, DECEASED; BY GEORGETTE IRENE MAYALL ADMINISTRATRIX, OF PHILADELPHIA, PENNSYLVANIA.

CARDBOARD-CREASING MACHINE.

Application filed March 14, 1924. Serial No. 699,304.

This invention relates to a cardboard creasing machine, and it relates more particularly to certain improvements in that type of machine for creasing card or other board for box making, shown and described in Letters Patent of the United States, granted to Lewis A. Mayall, February 2, 1915, No. 1,126,816.

In said Letters Patent No. 1,126,816, there is shown and described a machine by means of which longitudinal and transverse creases are formed in a sheet of cardboard while said sheet is being passed through the machine, and this without changing the plane or direction of travel of the sheet during the various manipulations to which the same is subjected to form the creases therein, it being understood that the sheet of cardboard is so creased for the purpose of subsequently forming the same into a portion of a paper box or container.

One of the principal objects of the present invention is to provide, in a machine of the character aforesaid, an improved construction and arrangement of the stops and the mechanism for actuating the same, for registering or positioning the sheet of cardboard as the same is subjected to the various manipulations of the machine, whereby said stops will be more positive, certain and reliable in their operation, as it is essential that said stops shall properly function at all times for the successful, efficient and economical operation of the machine.

A further object of the present invention is to provide improved means for adjusting certain of the creasing dies whereby the same may be quickly and readily changed in their locations for creasing sheets for boxes of various sizes.

The nature and characteristic features of the present invention will be more readily understood from the following description, taken in connection with the accompanying drawings forming part hereof, in which:

Figure 1 is a side elevation, to a certain extent diagrammatic, of a machine embodying the main features of the present invention;

Fig. 2 is an elevation of the front or feed end of the machine;

Fig. 3 is a fragmentary longitudinal section of the front or feed end portion of the

machine, the section being taken approximately on the line 3—3 of Fig. 2;

Fig. 4 is a fragmentary elevation of a portion of the machine, illustrating one of the stops and mechanism for actuating the same, the view being taken approximately on the line 4—4 of Fig. 3;

Fig. 5 is a fragmentary plan, taken approximately on the line 5—5 of Fig. 4;

Fig. 6 is a fragmentary horizontal section taken approximately on the line 6—6 of Fig. 2;

Fig. 7 is a fragmentary elevation, partly in section, taken on the line 7—7 of Fig. 6;

Fig. 8 is an enlarged plan of one of the stops for initially registering or alining the sheet of cardboard prior to its being fed through the machine; and

Fig. 9 is a section thereof, taken approximately on the line 9—9 of Fig. 8.

It should be understood that in the drawings there is shown so much only of the machine as is necessary for a proper understanding of the particular improvements of the present invention, and that, for a better understanding of the construction and operation of the machine in its entirety, reference is had to Letters Patent No. 1,126,816, dated February 2, 1915, to Lewis A. Mayall.

Referring to the drawings, in the particular embodiment of the present invention therein shown, α and α' are the side frames of the machine, from which the various parts thereof are supported. A feed table α^2 is provided at the front or feed end of the machine, and a discharge table α^3 is provided at the rear or discharge end of the machine, these tables being supported from the side frames α and α' as shown in Figs. 1, 2 and 3 of the drawings. The feed table α^2 is provided with an adjustable guide bar α^4 (see Figs. 1 and 2), for initially positioning the sheet of cardboard sidewise, thereby insuring that the longitudinal creases will be properly located upon the sheet as the same is operated upon in its passage through the machine.

The machine is preferably operated by an electric motor d , the shaft d^1 of which carries a pulley d^2 which, by means of a belt d^3 , drives a pulley d^4 mounted on a shaft d^5 , which also carries a gear d^6 . The gear d^6 meshes with a large gear d^7 , which in turn

meshes with and drives a gear d^8 . The gear d^8 is mounted on a shaft d^9 extending across the machine, the other parts of the mechanism above described being arranged on the 5 far side of the machine, as shown in Figs. 1 and 2 of the drawings.

The machine is provided with upper and lower longitudinal creasing dies c and c^1 , respectively. The upper creasing dies c are 10 adjustably secured to respective vertically reciprocable blocks c^5 and c^6 , and said upper creasing dies c are provided with members c^2 for forming the longitudinal creases in the sheet of cardboard. The particular 15 mechanism for vertically reciprocating the dies c through the medium of the blocks c^5 and c^6 , by which said dies are carried, as well as the construction of the dies themselves, form no part of the present invention, 20 and the same are fully shown and described in Letters Patent No. 1,126,816, hereinbefore referred to, and to which reference is had for a further understanding of the same.

The lower longitudinal creasing dies c^1 25 are supported on the cross bars c^4 , the same being arranged so as to be transversely adjustable in the machine and with respect to each other, to enable the machine thereby to be used for creasing blanks for boxes of 30 various sizes. For the purpose of facilitating the adjustment of one of said lower longitudinal creasing dies c^1 , there is provided the arrangement shown in detail in Figs. 6 and 7 of the drawings. This arrangement comprises the provision of a pair 35 of bolts c^{13} and c^{14} , threaded as at c^{15} , which respectively engage complementally threaded nuts c^{16} , which are secured to the under sides of the dies c^1 . The bolts c^{13} and c^{14} , and 40 consequently the nuts c^{16} , are spaced apart a sufficient distance so that, when the bolts c^{13} and c^{14} are actuated in unison, the die c^1 will be moved across the machine to the desired location, while at the same time 45 maintaining the proper longitudinal alignment of the same. On the ends of the threaded bolts c^{13} and c^{14} there are mounted gears c^{11} and c^{12} , respectively, each of which is engaged by a gear c^{10} mounted on a stud shaft c^8 , which is also provided with a hand wheel c^7 , the arrangement being such that when the hand wheel c^7 , is manually actuated, the bolts c^{13} and c^{14} will be synchronously rotated for the purpose of effecting the 50 adjustment of the lower creasing die c^1 , while at the same time maintaining the alignment thereof.

It will be noted that the means for adjusting the lower creasing dies is only shown 55 as applied to one of said dies on the right hand side of the machine (when viewed as in Fig. 2), as it will ordinarily be sufficient for all practical purposes to provide this convenient means of adjustment on but one 60 side of the machine, leaving the other die

to be adjusted as heretofore, for the reason that in ordinary practice the range of sizes required can be readily secured by the adjustment of but one of the longitudinal creasing dies.

On the near side of the machine, as shown in Fig. 1, a gear d^{10} is mounted on the cross shaft d^9 , hereinbefore referred to, which gear d^{10} meshes with and drives an idler gear d^{11} , which in turn meshes with and 70 drives a gear d^{12} . The gear d^{12} is mounted on a shaft d^{13} , upon which shaft d^{13} a cam d^{14} is mounted. A roller d^{15} engages the cam d^{14} , said roller being carried on the end of a lever d^{16} , which is secured to one end of a rock shaft a^{13} , which extends across the machine. The rock shaft a^{13} also carries, at each side of the machine, a lever d^{17} , which is connected by means of a link d^{18} to one end of a lever d^{19} , which is pivoted as at 80 d^{20} to a stationary part of the machine. The other end of the lever d^{19} is pivotally connected, as at d^{21} , to a link d^{22} . The link d^{22} on each side of the machine is connected at its lower end to the respective end of a bar a^{17} , 85 which extends across the machine. Near each end of the cross bar a^{17} there is provided a downwardly extending spring pressed rod d^{33} , the lower end of which is guided in a bracket d^{24} , which brackets d^{24} are respectively secured to the standards a and a^1 (see Fig. 2). The foregoing arrangement is provided for the purpose of normally impelling the cross bar a^{17} upward, except when the same is depressed by the actuation of the cam d^{14} , through the intervening mechanism hereinbefore described.

The gear d^{12} , hereinbefore referred to, also meshes with and drives a gear d^{25} , which in turn meshes with and drives a gear d^{26} , which 105 in turn meshes with and drives a gear d^{27} . The gear d^{27} is mounted on and serves to rotate the shaft a^{11} , which carries feed rollers a^{10} (see Figs. 1, 2 and 3). It should be understood that the feed rollers a^{10} are constantly 110 rotated during the operation of the machine. The rock shaft a^{13} which, as hereinbefore described, extends across the machine and is actuated by means of the cams d^{14} and the associated mechanism, carries levers a^{12} , 115 preferably of a flat spring type, and at the free end of each of the levers a^{12} there is carried a pressure roller a^9 . Each of the pressure rollers a^9 is adapted, when the same is lowered, to coact with a respective feed roller a^{10} , to feed the sheet of cardboard into the machine, it being understood that when the pressure rollers a^9 are raised, the feed rollers a^{10} will rotate idly on the under surface of the sheet of cardboard which may be 120 superimposed thereon.

Each of the lower creasing dies c^1 is provided with brackets a^7 , and in each of the brackets a^7 there is provided a vertically movable stop member a^5 , which is adapted 125

to be raised above the plane of the top surface of the die c^1 . The stop member a^5 is secured to and carried by a rack b . The rack b is engaged by a sector gear b^1 , which is mounted upon a shaft a^{14} , which shaft a^{14} extends parallel to the creasing die c^1 , so as to actuate the stops adjacent the respective ends thereof. The locations of the various stop devices employed for the complete creasing operation performed by the machine are more clearly shown and described in the hereinbefore mentioned Letters Patent No. 1,126,816, it being understood that the locations of said stop devices in the present invention are the same as in said Letters Patent, although the structure and mode of operation are different, as herein described.

The shaft a^{14} is also provided with a lever a^{15} , the free end of which is pivotally connected to one end of a link a^{16} . The other end of the link a^{16} is pivotally connected to a block b^2 , which engages the cross bar a^{17} hereinbefore described. The block b^2 is slotted complementary to the cross bar a^{17} , so that, when the corresponding die c^1 is adjusted crosswise in the machine, the block b^2 will engage the cross bar a^{17} at the various adjusted positions. The block b^2 is guided in its vertical movement by means of a bracket b^3 , which is secured to the die c^1 .

The gear d^{12} , hereinbefore referred to, also meshes with a train of gears d^{28} , for the purpose of actuating the feed rollers d^{29} in the central part of the machine, the purpose of which feed rollers is shown and described in said Letters Patent No. 1,126,816, hereinbefore referred to.

The gear d^7 , hereinbefore referred to, also meshes with and drives a gear d^{30} , mounted on a shaft d^{31} , which also carries a gear d^{32} , which in turn meshes with and drives a gear d^{33} . The gear d^{33} meshes with and drives a gear d^{34} , which in turn meshes with and drives a gear d^{35} , which in turn meshes with and drives a gear d^{36} , which in turn meshes with and drives a gear d^{37} . The gears d^{35} and d^{37} respectively serve to actuate the feed rollers d^{28} and d^{29} at the discharge end of the machine. The shaft d^{31} , upon which the gear d^{30} is mounted, serves to actuate the transversely extending creasing die near the discharge end of the machine, the construction and arrangement of this mechanism being the same as that shown and described in said Letters Patent No. 1,126,816, hereinbefore referred to.

The operation of the stop devices as contemplated by the present invention, and the associated mechanism for actuating the same, part of which is shown and described in said Letters Patent No. 1,126,816, will now be explained. The sheet of cardboard, or blank to be creased, is first placed upon the table a^2 , and is initially positioned with one edge thereof against the guide bar a^4 .

The cam d^{14} being in such position that the roller d^{15} bears against the low portion of said cam, the pressure rollers a^9 will be raised, through the action of the rock shaft a^{13} , upon which the levers a^{12} which support the roller a^9 are mounted. When the pressure rollers a^9 are thus raised, it will be understood that the cross bar a^{17} will be likewise raised through the intermediary of the lever d^{17} , link d^{18} , lever d^{19} and link d^{22} , the same being impelled upward by the spring pressed rod d^{23} . When the cross bar a^{17} is moved to the elevated position as aforesaid, the sector gear b^1 will be actuated by means of the lever a^{15} and shaft a^{14} . When the sector gear b^1 is thus actuated, the rack b will be correspondingly elevated, and consequently the stop members a^5 will be raised above the upper surface of the lower die c^1 . When the stop members a^5 are thus elevated, the sheet is pushed forward until the front end of the same abuts against said projecting stop members a^5 .

As the cam d^{14} continues to rotate until the high part thereof engages the roller d^{15} , the cross bar a^{17} will thereby be depressed through the intervening mechanism hereinbefore described, and thereby the sector gear b^1 will be actuated to lower end rack b , and consequently to lower the stop members a^5 carried thereby. Simultaneously, the rock shaft a^{13} being actuated, the pressure rollers a^9 will be depressed to cause the same to engage the sheet immediately over the lower feed rollers a^{10} , and in this manner the sheet will be fed forward until the front end of the same encounters the next set of stop members, which will be raised as the cam d^{14} continues to rotate, simultaneously with the elevation of the pressure rollers a^9 , the sheet meanwhile having reached the proper position to be arrested in its movement by said next set of stops. The sheet is thus fed forward through the machine, step by step, and subjected to the various manipulations of the creasing dies in the manner shown and described in said Letters Patent No. 1,126,816, hereinbefore referred to, being subsequently arrested in its movement for the manipulation by the transverse creasing die at the forward end of the machine by other sets of stops, not shown, but of substantially the same construction and arrangement.

Having thus described the nature and characteristic features of the present invention, what is claimed as new and desired to be secured by Letters Patent, is:—

1. In a machine of the character described, creasing dies, means for feeding a sheet to said creasing dies, stop devices having portions adapted to be projected into the path of said sheet to position the same during the creasing operation, said stop devices comprising a vertically movable member, a

4
rack to which said member is secured, a sector gear engaging said rack, and means for periodically actuating said sector to thereby raise and lower the vertically movable member.

2. In a machine of the character described, creasing dies, means for feeding a sheet to said creasing dies, stop devices having portions adapted to be projected into the path of said sheet to position the same during the creasing operation, said stop devices comprising a vertically movable member, a rack to which said member is secured, a sector gear engaging said rack, a shaft upon which said sector gear is mounted, and means for periodically actuating said shaft to thereby raise and lower the vertically movable member.

3. In a machine of the character described, creasing dies, means for feeding a sheet to said creasing dies, stop devices having portions adapted to be projected into the path of said sheet to position the same during the creasing operation, said stop devices comprising a vertically movable member, a rack to which said member is secured, a sector gear engaging said rack, a shaft upon which said sector gear is mounted, a lever carried by said shaft, a link pivotally connected to said lever, a block to which said link is connected, a bar extending across the machine and means for periodically raising and lowering said bar, said block being slidably mounted on said bar whereby the same will be properly positioned on said bar when the creasing dies are adjusted sidewise in the machine.

the machine and means for periodically raising and lowering said bar, said block being slidably mounted on said bar whereby the same will be properly positioned on said bar when the creasing dies are adjusted sidewise in the machine. 35

4. In a machine of the character described, creasing dies, means for feeding a sheet to said creasing dies, stop devices having portions adapted to be projected into the path of said sheet to position the same during the creasing operation, said stop devices comprising a bracket carried by the die, a vertically movable member mounted in said bracket, a rack to which said member is secured, a sector gear engaging said rack, a shaft upon which said sector gear is mounted, a lever carried by said shaft, a link pivotally connected to said lever, a block to which said link is connected, a bar extending across the machine and means for periodically raising and lowering said bar, said block being slidably mounted on said bar whereby the same will be properly positioned on said bar when the creasing dies are adjusted sidewise in the machine. 40 45 50 55

In witness whereof, I the said GEORGETTE IRENE MAYALL, administratrix of the estate of Lewis A. Mayall, deceased, have hereunto set my signature. 60

GEORGETTE IRENE MAYALL.
